UNITED STATES PATENT OFFICE.

CHARLES BALOUGH, OF SPRINGFIELD, OHIO.

GOVERNOR.

1,241,808.

Specification of Letters Patent.

Patented Oct. 2, 1917.

Application filed March 1, 1916. Serial No. 81,388.

To all whom it may concern:

Be it known that I, CHARLES BALOUGH, a subject of the Emperor of Austria-Hungary, residing at Springfield, in the county 5 of Clark and State of Ohio, have invented certain new and useful Improvements in Governors, of which the following is a specification.

My invention relates to improvements in 10 governors particularly adapted for regulating the intake valve of internal combustion engines, and more particularly relates to a governor of the type which employs the centrifugal force of a series of loosely 15 mounted balls.

The object of the invention is to provide 20 a governor of the type referred to which will be simple in construction, effective in operation and also one in which undue friction upon the balls is eliminated.

In the accompanying drawings,

The figure 1 is a vertical section of a governor embodying my improvements.

Referring to the drawings, a and a^1 represent 25 the parts of a sectional casing, the upper portion a' being provided with a screw-threaded neck a^2 upon which is threaded a cap a^3 . The lower section, a , of the casing is provided with a bushing, a^4 , within 30 which is journaled a shaft, b , which is continuously rotated by suitable driving connections (not shown) from the engine. The shaft, b , terminates at a point within the lower section, a , of the casing and has at the 35 upper end thereof an enlarged circular portion, c , which has a series of radially-arranged pockets, c' , within which are located balls, c^2 .

The upper end of the shaft, b , is bored 40 out and provided with a bushing, b' , within which is journaled the lower end of a stem, d , which is slidably mounted in a sleeve a^5 in the upper casing section, a^1 , formed integrally therewith. The stem, d , has integrally 45 formed therewith a circular housing d^1 inclosing and in contact with the balls c^2 . The stem, d , and housing, d^1 , are caused to revolve with the shaft, b , but at the same time are permitted a vertical movement relatively thereto, and for this purpose the shaft, b , is provided with a plate or ring, e , having a screwthreaded connection therewith, the outer edge of the plate being provided 50 with an upturned flange, e^8 , provided with a series of recesses, e^4 , within which are located balls, e^1 , which also extend into

vertically-arranged slots, e^2 , formed on the edge of the housing d^1 .

As the parts revolve the tendency is to throw the balls, c , outwardly by centrifugal force against an inclined surface, d^2 , on the interior of the housing, d^1 , and thus force the stem, d , upwardly against the tension of a spring g . As the stem moves upwardly it raises one end of a lever, f , connected with the valve controlling mechanism. A spring, g , which is a coil spring, surrounds a collar, g^1 , connected with the stem, d , and is confined between the upper side of the cap a^3 and a ring g^2 which is supported upon ball bearings g^3 laid on a projecting flange g^4 at the lower end of the collar g^1 . By this construction the spring, g , will remain stationary so far as rotary movement is concerned but the stem, d , and its collar, g^1 , will be permitted to revolve under the pressure of the spring.

Having thus described my invention, I claim:

1. In a governor, a rotatable part, a pocketed member directly connected with said rotatable part together with a series of movable devices arranged in said pockets, a second member having an inclined housing inclosing said devices, and a positive connection between said housing member and said rotatable part such as to cause the said member to rotate therewith but permit it to separate from said pocketed member under the action of said movable devices. 80

2. In a governor, a rotatable part, a pocketed member connected thereto to rotate therewith, a series of movable devices in the pockets of said member, a housing member inclosing said movable devices having an inclined surface, a third member connected with said rotatable part also having a series of balls, said housing member being provided with a series of slots into which said balls project to form a driving connection 85 between said housing member and said rotatable part. 95

3. In a governor, a rotatable part, a pocketed member directly connected with said part, a series of movable devices in the pockets of said member, a slidably mounted spring-pressed stem, a housing member connected with said stem inclosing said movable devices and having an inclined surface adjacent thereto, and a positive driving connection between said rotatable part and said housing member and stem to cause the same 100 105 110

- to rotate therewith but be allowed a movement relative thereto to permit said housing member to separate from said pocketed member.
5. 4. In a governor, a rotatable part, a stem slidably mounted relative to said part, separable members connected respectively to said stem and rotatable part one of which is provided with an inclined surface, a series 10 of movable devices between said separable members, connections whereby said members revolve with said rotatable part, a non-rotatable spring exerting its influence on said stem, and antifriction bearings between 15 said spring and stem to permit said stem to rotate relatively to said spring.

5. In a governor, a rotatable part, a stem 20 slidable with respect to said part, separable members connected respectively with said rotatable part and stem together with means for rotating said stem and the member connected thereto, a circular projection connected with said stem, antifriction bearings on said projection, a loose ring on said antifriction bearings, and a coil spring exerting 25 its influence on said ring.

In testimony whereof, I have hereunto set my hand this 23rd day of February 1916.

CHARLES BALOUGH.

Witness:

CHAS. I. WELCH.
